UNITED STATES PATENT OFFICE.

CIRO FIDEL MÉNDEZ, OF SAN LUIS POTOSI, MEXICO, ASSIGNOR OF ONE-HALF TO
ROBERTO YPINA, OF SAN LUIS POTOSI, MEXICO.

ROTATORY MECHANISM.

1,035,377.

Specification of Letters Patent. Patented Aug. 13, 1912.

Application filed August 5, 1911. Serial No. 642,463.

To all whom it may concern:

Be it known that I, CIRO FIDEL MÉNDEZ, citizen of Mexico, residing at San Luis Potosi, State of San Luis Potosi, Mexico, have 5 invented certain new and useful Improvements in Rotatory Mechanism, of which the following is a specification.

This invention relates to a new and useful improvement in devices for propulsion, 10 and relates more especially to the construction of a rotatory motor or propeller, as the device may be used either for generation of power or for utilization of power.

The object of the invention is the production of a device which will have a maximum of efficiency on its working stroke and a minimum of resistance on the recover.

The invention relates more particularly to a rotator provided with blades adapted 20 to be open on the working stroke, remain fixedly open for a portion of the stroke and be closed on the recover.

In the annexed drawings: Figure 1 represents a side view of the device in position 25 for operation. Fig. 2, an edge view looking in the direction of the arrow 22, Fig. 1. Fig. 3, an edge view looking in the direction of the arrow 3-3, Fig. 1. Fig. 4 is a side view of the rotator, one controller being 30 removed and showing the inner face of the other controller. Fig. 5 is an enlarged detailed section of a portion of the rotator showing the connection between the controllers and the blades of the rotator. Figs. 35 6, 7 and 8 show face, section and top views of a modified form of controller.

In these drawings: the numerals 1 and 2 indicate supports of any suitable kind, depending upon the mechanism to which the 40 invention is to be applied. These supports 1 and 2 carry at their upper ends 3 and 4 the controllers. These upper ends 3 and 4 have inner faces 5 and 6 which may be of any shape, but as shown in the drawings 45 are preferably oblique so as to be better adapted to hold the controllers 7 and 8. These controllers 7 and 8 are duplicates. They have flat backs 9 and 10 which rest against the oblique faces 5 and 6 of the supports 1 and 2, thus giving a flare to the controllers 7 and 8. The controllers 7 and 8 consist of two portions 11 and 12 which are substantially vertical with their inner faces parallel and the portions 13 and 14 having faces flaring outwardly from the

other faces. The exact configuration or shape of the inner faces is not important, except that there must be sufficient flare outwardly of these faces for the purpose of the invention. The inner faces of these 60 controllers 7 and 8 are provided with guide channels 15 in the present instance made by grooves in the controllers partially covered by plates 16 and 17 with spaces between them. These guide channels 15 are continuous, but have not the same curvature their entire length, being in two portions. The degree of curvature of the portions 18 in the outwardly flaring portions of the controllers differs materially from the degree 70 of curvature of the other portions 19 of the guide channel.

Passing through the centers of the controllers 7 and 8 and rotatable therein is the rotator shaft, to which between the controllers 7 and 8 is rigidly keyed the hub 20 of the rotator. Projecting radially from this hub are arms 21. These arms are preferably flat, being arranged edgewise in the plane of rotation. Each arm 21 is provided 80 with hinge loops arranged on opposite sides of the arm, in pairs, there being in the present instance three pairs of loops 22, 23, 24. Of these loops the pair 22 is at the end 25 of the arm 21 and the others 23, 24 are placed 85 near the hub 20 and close together with a small space between them. Hinged in these loops 22, 23, 24 are the blades 26, there being a pair for each arm 21. The blades consist of an outer supporting rim 27 and plates 28 secured to such rim across the blades 26. The inner bars 29 of the rims 27 are loosely held in the hinge loops 22, 23, 24. These blades are usually made somewhat paddle-shaped, as shown, the broader portions being 90 at the outer ends.

Connected to and projecting from the lower ends 31 of the outer bars 30 of the rims 27 are guide arms 32. These guide arms 32 are at an angle to the planes of the blades 26 and also extend outwardly therefrom and slightly downwardly or toward the hub 20. The ends 33 of these guide arms 32 pass through the slots into the guide channels 15 and carry the travelers 34 which may be any kind of anti-friction devices. In Fig. 5 is shown one kind, an axle 35, with the two wheels 36, 36.

When the device is used for the application of power, as a propeller, power is ap- 110

plied to the shaft turning the rotator. This causes the blades to press against the element, air or water, in which they are re-
 5 volved. As the rotator is turned the trav-
 elers move in the guide channels. And the
 blades are caused to be opened or closed,
 that is, to be moved together or apart, as
 the travelers are in different parts of the
 10 guide channels. When the travelers are in
 the portions of the guide channels in the
 vertical portions of the controllers the blades
 are closed on the recover, that is, when they
 are not working. As the travelers leave
 15 the portions of the guide channels in the
 vertical portions of the controllers and enter
 the portions in the flaring portions of the
 controllers the flare of these portions of the
 controllers causes the travelers to move out-
 20 wardly and by means of the guide arms to
 move the blades apart. As the travelers
 move along the tops of the guide channels
 the blades remain fixedly open for a space
 25 of time until the travelers leave these por-
 tions of the guide channels. The length of
 time depends upon the configuration of the
 portions of the guide channels in the flaring
 30 portions of the controllers. In Figs. 1 and
 4 is shown one form. Here there is a de-
 cided and extended flattening or an enlarged
 35 curvature at the top of the guide channel.
 This flattening or enlarged curvature is co-
 incident with the working stroke or the
 maximum efficiency of the device, and in-
 surens that the blades shall remain open for
 40 a large portion of the working stroke. In
 Fig. 6 there is a slight portion somewhat
 flattened or of much greater curvature than
 the rest of the guide channel. Hence for a
 limited duration of time as the travelers
 45 pass along such portions of the guide chan-
 nels the blades will remain open and will
 be closed sooner than in the other form.
 From the above it will be perceived that
 50 the desired efficiency of the device is ob-
 tained by the union of the two features, the
 flare of the controllers and the configura-
 tion of the tops of the guide channels. The
 flare causes the blades to be opened and
 55 closed. Were the channels circular from the
 center of rotation there would be a move-
 ment in and out of the blades. But with the
 configuration of the portions of the guide
 channels in the flared portions of the con-
 trollers such portions of the guide chan-
 nels being flattened or of much greater cur-
 vature than the other portion of the guide

channel, the blades remain fixedly open for
 a portion of the stroke, the extent of time
 depending upon the length of such flattening
 or greater curvature. 60

Such a device is capable of use in many
 places. It may be used as a propeller, as al-
 ready stated. Or it may be used as a motor,
 power being applied to the blades and trans-
 mitted through the shaft. It may be lo-
 65 cated in any position, the flaring portions
 of the controller being arranged so that the
 blades shall be at the proper place for the
 efficiency stroke coming on top or beneath,
 as desired. If the flattened portions or por-
 70 tions of greater curvature of the guide chan-
 nels be not of great extent, as, for instance,
 shown in Fig. 6, there will be given to the
 blades a quick action similar to the flapping
 75 of the wings of a bird, and such form is es-
 pecially applicable for use for a motor for
 aeroplanes.

The controllers may be so placed in rela-
 80 tion to each other and the guide bars 32
 have such length that the plates may be
 fully opened or in the same plane when at
 their maximum stroke or they may be not
 fully opened, but at an angle to each other. 85

Having described my invention, what I
 claim is:

1. A rotator provided with blades in pairs
 and adapted to be opened and closed in
 combination with controllers, one on each
 side of the pairs of blades, such controllers
 having continuous guides, each of two cur-
 90 vatures, the curvatures being of two por-
 tions, one of which is greater than that of
 the other and guide arms extending from
 the blades and engaging the guides of the
 controllers. 95

2. A rotator provided with blades in pairs
 and adapted to be opened and closed and
 having guide arms, in combination with con-
 trollers consisting of vertical and flaring
 100 portions and provided with a guide channel
 in such portions, the portions of the guide
 channel in the flaring portions of the con-
 trollers being of greater curvature than
 105 those portions in the vertical portions of the
 controllers, the guide bars extending into
 such guide channels and engaging the same.

In testimony whereof I affix my signature
 in presence of two witnesses.

CIRO FIDEL MÉNDEZ.
